(57) **CLAIM**

The ornamental design for a stabilizer for a water scooter, as shown and described.

DESCRIPTION

FIG. 1 is a front elevational view of a stabilizer for a water scooter showing our new design;

FIG. 2 is a rear side elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an end view taken along the line 7—7 in FIG. 1; and,

FIG. 8 is a reduced reference view of the stabilizer for a water scooter from the rear perspective of a water scooter in position of use.

The broken lines are for illustrative purposes only and form no part of the claimed design.
